UNITED STATES PATENT OFFICE.

ALBERT JOHN LOEPSINGER, OF PROVIDENCE, RHODE ISLAND, ASSIGNOR TO GENERAL FIRE EXTINGUISHER COMPANY, OF PROVIDENCE, RHODE ISLAND, A CORPORATION OF NEW YORK.

PIPE-HANGER.

1,134,395.

Specification of Letters Patent.

Patented Apr. 6, 1915.

Application filed August 28, 1911. Serial No. 646,420.

To all whom it may concern:

Be it known that I, ALBERT J. LOEPSINGER, a citizen of the United States, residing at Providence, in the county of Providence and State of Rhode Island, have invented new and useful Improvements in Pipe-Hangers, of which the following is a specification.

In equipping factories with piping, and particularly with the pipes employed in automatic sprinkler systems, it is frequently desirable to suspend the pipes from the flanged bottoms of I-beams, and my invention is particularly intended to provide a form of pipe hanger by means of which a pipe may be securely supported as above described without making it necessary to employ or keep in stock different sizes of some or all of the parts of the hanger to correspond with all the different thicknesses of I-beam flanges. To this end I have devised certain improvements which are hereinafter described and are illustrated in the accompanying drawings, in which—

Figure 1 is a side elevation showing one form of my hanger as preferably constructed; Fig. 2 is a section on the line $x-x$ in Fig. 1; and Fig. 3 is a view similar to Fig. 1 but showing the hanger applied to an I-beam having thinner flanges.

In Fig. 1 of the drawings, 2 represents the lower portion of an I-beam having the usual flanges 3 at its bottom, and 4 represents a hook-shaped jaw member adapted to receive one of the flanges 3 within its jaw and to be clamped upon the same by means of a rod 5 passing transversely beneath the bottom of the beam 2 and having a hook 6 at one end to receive the opposite flange 3, the opposite end of said rod being passed through an opening 7 in the jaw member 4 and threaded to receive a nut 8 whereby the jaw member and the hook 6 may be drawn together and thus secured firmly to the bottom of the beam 2.

The parts above referred to, generally speaking, are similar to those of a form of pipe hanger heretofore employed, but in the prior form of hanger the jaw member has been shaped to fit a flange of given thickness, and therefore it has been necessary to provide jaw members of different sizes in correspondence with the different thicknesses of flanges found on I-beams. According to my present invention, however, I provide

the jaw member 4 with a jaw of such size as to be capable of receiving an I-beam of any given thickness, within a considerable range, and I give to this jaw a peculiar contour whereby the necessary points of contact between said jaw and the flange of the I-beam are maintained regardless of the exact thickness of the flange. This peculiar contour is illustrated in Fig. 1, in which the jaw member 4 is so shaped as to provide an overhanging top portion having a downwardly-facing surface 9 adapted to rest upon the top of the I-beam and thus support the weight of the suspended parts, an intermediate surface having a curved outline, as shown at 10, and adapted to bear against the adjacent edge of the flange 3 in opposition to the hook 6 and thus resist the clamping pressure of the nut 8, and a forwardly-extending under portion having an upwardly-facing surface 11 adapted to bear against the under side of the I-beam and thus prevent the jaw member from rocking upon the edge of the flange 3 when the jaw member and the hook 6 are drawn together by screwing up the nut. Thus there are three points of contact between the jaw member 4 and the flange 3, the curved surface 10 being so shaped with respect to the surfaces 9 and 11, that engagement between the jaw member and the flange at these three points will always be secured, whatever the thickness of the flange may be. Thus in Fig. 3 the same jaw member illustrated in Fig. 1 is shown as applied to a flange 3' of less thickness than the flange 3, but in this case also, although the jaw member 4 is tilted somewhat as compared with its position illustrated in Fig. 1, the three bearing surfaces above described engage the corresponding surfaces of the flange and thus provide the desired resistance and support at these points.

The opening 7 in the jaw member 4, through which the rod 5 passes, is made large enough to enable the jaw member to take any one of its clamping positions without affecting the position of said rod, and in order that the hook 6 at the end of this rod may also be adapted for use in connection with I-beam flanges of different thicknesses, said hook is preferably shaped in the first instance as shown in dotted lines in Fig. 1, its free end being hammered over upon the I-beam, as shown in full lines in

said figure, after the hanger has been clamped in place.

In addition to the parts above described my hanger includes suitable means for suspending a pipe from the jaw member 4, and any desired form of pipe-supporting device suitable for use with a hanger of this type may be employed for this purpose. By way of example I have shown in Fig. 1 a supporting device comprising a link 12 pivotally suspended at its upper end from the jaw member 4 and having a horizontal flanged bearing 13 at its lower end about which a pipe-supporting link 14 is adapted to swivel, thus permitting the pipe to be given any desired direction with respect to the length of the I-beam 2.

It is not necessary that the jaw member above described be adapted for use with I-beam flanges of all possible thicknesses, since the object of my invention will be substantially accomplished, as a practical matter, by providing a few different sizes of jaw member and using that size which is most suitable in any given instance.

I claim as my invention:—

1. A pipe hanger comprising a jaw member shaped to provide three projecting bearing surfaces adapted to bear simultaneously upon the top, bottom and one edge of an I-beam flange having any one of several thicknesses and hold said jaw rigidly and against rocking in whatever position it may assume, a co-operating clamping member adapted to engage the I-beam and passing through a vertical slot in the jaw member to permit adjustment of parts to the thickness of said I-beam flange, and a pipe supporting device pivotally depending from said jaw member.

2. A pipe hanger comprising a jaw mem-

ber having an upper portion provided with a downwardly-facing bearing surface, a lower portion extending beyond the top portion in the same direction and provided with an upwardly-facing bearing surface, and an intermediate bearing surface formed on a curved line and projecting into the jaw formed by said upper and lower portions of the jaw member, means for clamping said jaw member upon an I-beam flange, with said bearing surfaces in contact respectively with the top, bottom and edge of the flange, and a pipe-supporting device carried by said parts.

3. A pipe hanger comprising a body member from one side of which project two vertically spaced fingers, a bearing surface formed on the under side of the upper finger, a second bearing surface formed on the upper face of the lower finger, and a third bearing surface formed on the body member between said fingers, said bearing surfaces being so related one to the other as to always engage the top, bottom and adjacent edge of an I-beam flange having any one of various thicknesses and hold the hanger from rocking, a clamping member extending through a vertical elongated opening in the body member to permit angular adjustment to position of said body member on I-beams of different thicknesses, and a swiveled pipe supporting device pivotally depending from the body member.

In testimony whereof, I have hereunto subscribed my name this 25th day of August, 1911.

ALBERT JOHN LOEPSINGER.
